[57] CLAIM

The ornamental design for an eyeglass frame, as shown and described.

DESCRIPTION

FIG. 1 is a perspective view of the eyeglass frame showing my new design;

FIG. 2 is a front elevational view thereof on an enlarged scale;

FIG. 3 is a cross-sectional view thereof as seen on line 3—3 of FIG. 2.

FIG. 4 is a top plan view thereof on an enlarged scale;

FIG. 5 is a side elevational view thereof on an enlarged scale.

The temples are omitted in FIGS. 2 and 3 for convenience of illustration.

It is noted that the right and left side plan views are the same.

FIG. 1

FIG. 3

FIG. 2

FIG. 4

FIG. 5
